(57) **CLAIM**

The ornamental design for a marine infant seat, as shown and described.

DESCRIPTION

FIG. 1 is a perspective view of the marine infant seat showing my new design;

FIG. 2 is another perspective view of the marine infant seat; FIG. 3 is another perspective view of the marine infant seat; FIG. 4 is a perspective view of the marine infant seat with the tray removed for ease of illustration, wherein other views of FIG. 4 being similar to the views of the marine infant seat shown in FIG. 2;

FIG. 5 is a side view of FIG. 1;

FIG. 6 is the opposite side view of FIG. 1;

FIG. 7 is a front view of FIG. 1;

FIG. 8 is a top view of FIG. 1;

FIG. 9 is a rear view of FIG. 1;

FIG. 10 is a bottom view of FIG. 1; and,

FIG. 11 is another bottom view of FIG. 1.

The broken lines shown in the drawings are for illustrative purposes only and form no part of the claimed design.
